(57) **CLAIM**

The ornamental design for a wire mount connector, as shown and described.

DESCRIPTION

FIG. 1 is a front view of the wire mount connector of FIG. 1.

FIG. 2 is a rear view of the wire mount connector of FIG. 1. FIG. 3 is a right side view of the wire mount connector of FIG. 1.

FIG. 4 is a top plan view of the wire mount connector of FIG. 1.

FIG. 5 is a bottom plan view of the wire mount connector of FIG. 1; and,

FIG. 6 is a sectional view taken along line 6—6 of FIG. 1. The broken line showing of the environment is for illustrative purpose only and forms no part of the claimed design.
